UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

AUTOMATIC MUSICAL INSTRUMENT OR PLAYER.

No. 843,755.

Specification of Letters Patent.

Patented Feb. 12, 1907.

Application filed June 3, 1905. Serial No. 263,628.

To all whom it may concern:

Be it known that I, PAUL BROWN KLUGH, a citizen of the United States, residing at Chicago, in the county of Cook and State of Illinois, have invented new and useful Improvements in Automatic Musical Instrument or Player, of which the following is a specification, reference being had to the accompanying drawings, forming a part thereof.

This invention relates to automatic musical instruments, commonly called "players" for musical instruments, and its purpose is to provide improved means operated by the various stops and levers for regulating the playing both as to speed and intensity and for adjusting the means which carry the perforated controlling-sheet relatively to the tracker-board for accurate registration and other purposes for which such adjustment may be serviceable.

It consists of the features of construction set out in the claims.

In the drawings, Figure 1 is a plan view of the mechanism of an automatic player embodying my improvements, the top cover removed and other parts omitted and broken away. Fig. 2 is a partly-sectional rear elevation of the same mechanism, section being made at the line 2 2 on Fig. 1 through the valve-boxes and the air-chamber of the pneumatic-action. Fig. 3 is a partly-sectional bottom plan view of the lever connections from the stops to the different valves which they operate, the front board being cut in horizontal section at a plane below the levers. Fig. 4 is a detail section at the line 4 4 on Fig. 3. Fig. 5 is a detail section at the line 5 5 on Fig. 1, showing the governor, which would also appear similarly in a section at the line 5^a 5^a on Fig. 1.

Certain elements in this structure are of familiar form and will not be described, but only mentioned for identification.

1 is the air-chamber of the pneumatic-action of a pneumatically-operated automatic player of the general type which employs primary pneumatics 2 2 2 in such chamber for controlling the action of motor-pneumatics which actuate the strikers for striking the keys, such motor-pneumatics and the connections between them and the primary pneumatics being not shown, but being of familiar construction. The customary tracker-board 3, rolls 4 4^a for carrying the perforated control-

ling-sheet, (not shown,) wind engine or motor 55 comprising three bellows 5 5, and the triple-cranked shaft 6, the train 7, driven by such motor for operating the rolls, and the wind-chest or main vacuum-chamber 8 are in general of usual construction and for the purpose 60 of understanding the inventions involved in this case require no further particular description except as to certain minor details, which will be described hereinafter in their proper connection with the specific improvements 65 constituting the present invention.

In the train 7 the shaft 9 is continuously driven by the chain 10, connecting it with the main crank-shaft 6, and the pinion 11 on the inner end of said shaft 9 being arranged to 70 mesh with the gear 12 on the shaft of the take-up roll 4^a, is carried into and out of mesh with said gear 12 by the lever 13, whose finger 13^a engages the hub of the sprocket-wheel 14, which is fast on the shaft 9 to slide the latter 75 longitudinally in its bearings. Said hub is one member of a clutch having a driving-finger 14^a, carried into engagement with the finger 15^b of the gear 15 by the sliding of the shaft in a direction and to a distance sufficient to carry the pinion 11 out of mesh with the gear 12, and by the engagement of the clutch when the shaft is thus moved the rewinding movement is communicated to the 80 take-up roll 4 in the opposite direction to the 85 take-up movement of the roll 4^a. The lever 13 is operated by the link 16, which connects said lever with the stop-lever 17, (see Fig. 3,) whose stop-finger 17^a projects through the slot 17^b in the stop-board, the lever itself being fulcrumed at 17^c on the lower side of the stop-board. On the lower side of the stop-board there is mounted the rock-shaft 18, which has a lever-arm 18^a, projecting rearward and provided with an obliquely-extending finger or crank-wrist 18^b, which protrudes under the lever 17 near the forward end of the latter, said lever having on its under side a beveled abutment 17^d, facing the finger 18^b, so that as the lever is moved to the left for 90 throwing the driving-train in connection with the rewind-roll and disconnecting the take-up roll said abutment 17^d, encountering the beveled crank-finger 18^b, rocks the shaft 18 in its bearings. The spring 19 operates on the shaft 18 to hold the lever-arm 18^a up against the under side of the stop-board, and the rock-shaft 18 has at the opposite end a le-

ver-arm 18°, which at the normal position in which the shaft is held by the spring stands across the path of an abutment or finger 20^a, which is provided on a lever 20, fulcrumed on the lower side of the stop-board and having at its forward end a stop-finger 21, protruding up through a slot 22 in the stop-board. This lever 20 at its rear end is connected by a link 23 with the lever 24, fulcrumed on the back of the front board 25, and connected at its lower end with the valve-rod 26, which operates the valve hereinafter described for controlling the supply of air to the pneumatic-action and by which, therefore, the intensity 15 of the playing is regulated.

The stop-lever 20 is hereinafter referred to as the "accent-lever" and its stop-finger 21 as the "accent-stop," because its purpose is to accent the music by varying the intensity 20 as it is moved in one direction or the other.

The purpose of the connection described between the stop-lever 17, which controls the connection of the driving-train with the rewind and take-up roll, respectively, and which 25 is commonly called the "rewind-lever," and the lever 24, which controls the accent, is directly related to the construction of the valve mechanism which the accent-stop controls. This valve mechanism is shown in Fig. 2. It 30 comprises the valve-box 27, which has two connections with the wind-chest 8, through the ducts 28 and 29. The connection by the duct 28 includes a governor, such as shown in Fig. 5; but the duct 29 connects directly with 35 the wind-chest. A valve 30 is arranged to slide over the mouth of the duct 28 within the valve-box, and a spring 31, connected to a post 32 in the box, operates to hold the valve in open position, as shown in Fig. 2. A 40 valve 33 is arranged to slide similarly over the mouth of the duct 29. This latter valve is connected to the valve-rod 26, and said rod is also extended through the post 32, so that with sufficient stroke it may collide with the 45 upstanding finger 30^a of the valve 30 and move the latter valve to close it. When both the valves 30 and 33 are wide open, the full suction from the wind-chest operates through, the valve-box and the duct 28 and 29, connecting it with the air-chamber of the pneumatic-action to give the most powerful action, to the strikers, and under these conditions, the intensity of the stroke is limited only by the force of the pumping up to the limit of the 50 tension which can be maintained in the wind-chest, which is limited and varied by means well understood; but when the valve 33 is closed the governor (see Fig. 5) limits the tension operative upon the pneumatic-action to 55 that for which the governor is adjusted, which will be such as to produce the softest playing desired. By moving the valve 33 more or less over the mouth of the duct 29 the playing may be graduated from the softest, which is 60 produced under the action of the governor, to

the loudest, which would be produced when the valve 33 is wide open, and the accent-stop 21 is moved to graduate the opening of the valve 33 from the position at which it is shown in Fig. 3 to about the middle of the slot 22, and its further movement in direction for opening the valve is prevented by the collision of the finger 20^a with the lever-arm 18° of the rock-shaft 18.

When the motor mechanism for operating the rolls is set for rewinding, the air communication of the pneumatic-action with the wind-chest should be entirely cut off, so that no playing will result from the reverse movement of the controlling-sheet or the tracker-board. In order to close not only the duct 29, but the duct 28, it is necessary that the lever 24, connected with the accent-stop 21, should be moved past the point at which it is operated to merely close the duct 29, and in 80 order that it may be thus moved only when the motor mechanism is set for rewinding the rock-shaft 18 and its connections above described with the lever 17 are provided, for it will be observed that when the lever 17 is 85 moved to the left for setting the train in connection with the rewind-roll the finger 18° of the rock-shaft 18 is moved out of the path of the lever 20 and that the accent-stop 21 on that lever may then be moved to the limit of 90 the slot 22, causing the head of the valve-rod 26 to encounter the upstanding abutment 30^a of the valve 30 and carry that valve over the mouth of the duct 28, closing the same, while the valve 33, having already closed the 95 mouth of the duct 29, continues to move over the duct without unclosing it, being wide enough to have such range of movement while still covering the duct.

The pneumatic motor for driving the train and rolls communicates with the wind-chest, from which the power is derived through the valve-box 34. This valve-box has two connections with the wind-chest, one through the duct 35, which leads directly into the 100 wind-chest, and the other through the duct 36, which leads to the wind-chest through governor 37. (See Fig. 5.) The mouths of these two ducts in the valve-box are controlled by valves 40 and 41, respectively. 105 The valve 41 is operated by the lever 42, fulcrumed at 43 on the rear side of the front board and connected at its upper end by means of a link 44 with the rear end of the tempo-stop lever 45, at whose forward end 110 the tempo-stop 46 projects up through the slot 47 in the stop-board. The movement of the tempo-stop 46 to the extreme left of the slot causes the valve 41 to close the mouth of the duct 36, and its movement toward the 115 right opens the mouth of the duct more or less, according to distance, and thereby enables the operator to control the amount of air drawn through the motor and the resulting speed of rotation and of the playing or 120 125 130

tempo of the music up to the maximum speed determined by the adjustment of the governor 37. For exceptional acceleration the valve 40 may be opened more or less to give the motor direct communication with the wind-chest, and for that purpose this valve has its operating-rod 48 connected to the lower end of the lever-arm 49 on the rock-shaft 50, mounted on the under side of the stop-board and having at its forward end a lever-arm 51, connected with the stop-button 52, which extends up through the stop-board, a spring 53 being provided at any convenient point in the connections described for holding the valve in closed position. The spring is illustrated as connected to the lever-arm 49 and to the valve-box 34, operating in proper direction for closing the valve 40. The stop-button 52 will be depressed for opening the valve 40 not only for exceptional acceleration of the playing, but for rewinding, being held down during the entire time of rewinding. The operator will therefore depress this stop-button whenever the 25 wind-stop 17* is operated for rewinding.

I claim—

1. In an automatic musical instrument or player, in combination with the wind-chest and the air-chamber of the pneumatic-action, 30 two passages connecting them; a separate valve for each passage; a governor in one passage between the valve and the wind-chest; a stop for operating both valves and connections by which the movement of the stop in 35 one direction closes the valves, one after the other.

2. In an automatic musical instrument or player, in combination with the wind-chest and the air-chamber of the pneumatic-action, 40 two passages connecting them; a governor in the first passage, and a valve controlling the passage between the governor and the air-chamber; a gradually-closing valve in the second passage; a stop for operating both 45 valves and connections from said stop to the valves respectively by which the movement of the stop in one direction first closes the second valve and afterward closes the first.

3. In an automatic musical instrument or 50 player, in combination with the wind-chest and the air-chamber of the pneumatic-action, two passages connecting them; a governor in one passage; a valve for the governed passage; a separate gradually opening and closing valve for the other passage; a stop and connections by which it operates the second valve for gradual opening and closing, and additional connections by which it operates the first valve by a range of movement not 55 included in that by which it opens and closes the second valve.

4. In an automatic musical instrument or player, in combination with the wind-chest and the air-chamber of the pneumatic-action, 60 a valve-box; a passage connecting it with the

air-chamber; two passages connecting it with the wind-chest; a governor in one of said two passages; a valve in the valve-box controlling said governed passage; a second valve in the box controlling the other passage and 70 movable independently of the first valve; means holding the first valve normally fully open; means for gradually opening and closing the second valve; a stop for operating said means and connections operated by the 75 stop for closing the first valve while the second valve remains closed.

5. In an automatic musical instrument or player, in combination with the wind-chest and the air-chamber of the pneumatic-action, 80 a valve-box; a passage connecting it with the air-chamber; two passages connecting it with the wind-chest; a governor in the first of said passages; a valve normally open controlling said passage; a valve for controlling the second passage; a longitudinally-reciprocating rod protruding from the valve-box connected therein with the second valve, and abutments on the rod and on the first valve which collide for seating the first valve after the rod 85 is moved longitudinally for fully closing the second; a stop and connections therefrom for reciprocating the rod.

6. In an automatic musical instrument or player, in combination with the pneumatic- 95 action; two passages through which it derives, respectively, higher and lower tension; valves controlling such passages respectively; an accent-stop and connections therefrom for closing the higher and lower tension-valves 100 in the order named, by movement of the stop in one direction; a stop-arresting device; a rewind-stop and connections therefrom for withdrawing the stop-arresting device.

7. In an automatic musical instrument or 105 player, in combination with the wind-chest and the pneumatic-action; means for controlling the communication between them for varying the intensity of the playing comprising a governed passage and an ungoverned 110 passage; a separate valve for each passage; an accent-stop and connections therefrom to the valves whose movement in one direction closes first the valve in the ungoverned passage and afterward the valve in the governed 115 passage; the roll-actuating mechanism and its controlling devices comprising a rewind-stop; means which normally arrest the accent-stop at the limit of the movement which closes the first valve, and connections thereto 120 from the rewind-stop for withdrawing the arresting device.

8. In an automatic musical instrument or 125 player, in combination with the pneumatic-motor and the wind-chest, two passages connecting them; a valve controlling each passage; a governor in one passage between the wind-chest and the valve; a tempo-stop and connections by which it operates the valve of the governed passage; a rock-shaft having 130

two lever-arms; connections from one of them for operating the valve of the ungoverned passage; a stop-button connected with the other arm and a spring which acts on the 5 rock-shaft to hold the last-mentioned valve closed and the stop-button protruded.

9. In an automatic musical instrument or player, in combination, a wind-chest; a pneumatic-action; a playing and rewind stop, and 10 means by which said stop controls the communication of the pneumatic-action with the wind-chest; a pneumatic motor; two communications between the motor and the wind-chest; a governor in one of said communica-

tions; a tempo-valve for controlling said governed communication; a separately-operated valve controlling the ungoverned communication; an accelerando-stop and connections for operating thereby the last-mentioned valve independently of the action of the playing and rewind stop. 15

In testimony whereof I have hereunto set my hand, at Chicago, Illinois, this 22d day of May, A. D. 1905.

PAUL BROWN KLUGH.
